COMBINED FIREPLACE SMOKE CHAMBER AND DOWNDRAFT SHELF

George F. Haney, 536 S. Indiana, Anaheim, Calif.
92805, and Woody G. McClain, 4377 S. Huron, Engle-
wood, Colo. 80110

Filed Dec. 23, 1971, Ser. No. 211,832

Term of patent 14 years

Int. Cl. D23—03

U.S. Cl. D23—94

FIG. 1

FIG. 2

FIG. 3

FIG. 4

FIG. 5

FIG. 6

FIG. 1 is a perspective view showing the front, top, and right sides of a combined fireplace smoke chamber and downdraft shelf showing our new design;

FIG. 2 is a perspective view showing the bottom, rear, and right side of the combined fireplace smoke chamber and downdraft shelf design;

FIG. 3 is a top plan view of the combined fireplace smoke chamber and downdraft shelf design;

FIG. 4 is a front elevation view of the combined fireplace smoke chamber and downdraft shelf design;

FIG. 5 is an elevation view of the right side of the combined fireplace smoke chamber and downdraft shelf design; and

FIG. 6 is a vertical section through the center of the combined fireplace smoke chamber and downdraft shelf design.

We claim:

The ornamental design for a combined fireplace smoke chamber and downdraft shelf, as shown.
